THIGH PAD

John H. Rawlings, Ava, Mo., assignor to Questor Corporation, Toledo, Ohio

Filed Dec. 6, 1971, Ser. No. 205,455

Term of patent 14 years

Int. Cl. D2—02
U.S. Cl. D2—27

FIG. 1

FIG. 2

FIG. 3

FIG. 4

FIG. 5

FIG. 1 is a front elevational view of a thigh pad showing my new design;

FIG. 2 is a side elevational view thereof;

FIG. 3 is a top plan view;

FIG. 4 is a side perspective view; and

FIG. 5 is a cross sectional view taken on the line 5—5 of FIG. 1.

I claim:

The ornamental design for a thigh pad, as shown.
